Primary Examiner — Philip S Hyder*Assistant Examiner* — Cary M Robinson(74) *Attorney, Agent, or Firm* — Harness, Dickey & Pierce, P.L.C.(57) **CLAIM**

The ornamental design for a lacrosse glove, as shown and described.

DESCRIPTION

FIG. 1 is a perspective view of a lacrosse glove embodying my new design;

FIG. 2 is a top plan view of the lacrosse glove of FIG. 1; FIG. 3 is a bottom plan view of the lacrosse glove of FIG. 1;

FIG. 4 is a left side view of the lacrosse glove of FIG. 1; FIG. 5 is a right side view of the lacrosse glove of FIG. 1; FIG. 6 is a front view of the lacrosse glove of FIG. 1; and, FIG. 7 is a rear view of the lacrosse glove of FIG. 1.

(Continued)

It is to be understood that the broken lines in the accompanying figures illustrate portions of the lacrosse glove in which the design is embodied that form no part of the claimed design.

1 Claim, 7 Drawing Sheets
